EDGE RUNNER MILL

Karl Bruchsaler, Stockton, Calif.

Application August 25, 1944, Serial No. 551,155

7 Claims. (Cl. 241—41)

1

This invention relates to pulverizing machines of the edge runner mill type.

An object of the invention is to provide a pulverizing mill of the edge runner type or machine for crushing ore or grinding various substances or materials with greater efficiency and in high comparative quantities without the danger of clogging or jamming of the machine by accumulation of the ore or the like.

Another object of the invention is to provide a pulverizing mill of the edge runner type in which material can be crushed or ground in a continuous operation and in which the crushing is accomplished by a plurality of heavy roller wheels positively guided or moved on a surface rotated in a direction opposite to the direction of rolling of said wheels, and in which the material is fed to the race in such a manner as to efficiently find its way on the race, and thereafter the crushed material be conveniently discharged only when it is crushed to a predetermined consistency and then collected and conducted to a convenient outlet.

Another object of the invention is to provide a pulverizing mill of the edge runner type in which a plurality of heavy rollers with crusher shoes are rolled upon a race and suitable liquid is discharged alongside the rollers toward the race, and in which the material to be crushed is fed for even distribution around the entire race and the entire path of said rollers, and in which the discharge of the crushed material is conveniently controlled and guided.

With the above mentioned objects and other objects in view, the invention consists in the novel construction and combination of parts hereinafter described, illustrated in the accompanying drawings, and set forth in the claims hereto appended, it being understood that various changes in the form, proportion, size and minor details of construction within the scope of the claims may be resorted to without departing from the spirit or without sacrificing any of the advantages of the invention.

With the foregoing and other objects in view, which will be made manifest in the following detailed description, reference is had to the accompanying drawings for the illustrative embodiment of the invention, wherein

Fig. 1 is a sectional view of my pulverizing mill.

Fig. 2 is a plan view of my pulverizing mill.

Fig. 3 is a sectional plan view of my pulverizing mill, the section being taken on lines 3—3 of Fig. 1, and

2

Fig. 4 is a sectional detail view, the section being taken on lines 4—4 of Fig. 1.

In its general organization my invention includes a base 1, a race structure 2 rotatably supported on the base, a rotatable crushing mechanism 3 which drives and rolls heavy crusher rollers 4 on the race structure 2, and a drive mechanism 6 connected to both the race structure 2 and the crushing mechanism 3 for driving them in opposite directions to each other.

The base 1 may be of any suitable construction, but it is preferable that the same be made of a welded structure of angle irons. This base 1 includes ground bars 7 from which extend upwardly vertical stays 8, a central hub 9, an outer peripheral rim 11, and a plurality of radial beams 12 extended between the hub 9 and the rim 11 and forming the top of the base 1. On each of the beams 12, and equidistant from the center of the hub 9 are provided a pair of bearing brackets 13 so positioned that the journal axes of the bearing brackets 13 are radial with respect to the center of the hub 9 and substantially parallel with the respective beams 12. In each pair of bearing brackets 13 is journaled a shaft 14 on which is supported a gear 16.

The race structure 2 includes a race frame 17. In the present form the race frame is in the shape of a substantial and strong ring, which, in the present illustration, is cast and is hollow so as to reduce the weight of the rotating race structure 2. From the bottom of this race frame 17 extends a ring gear 18 which is of the same radius as the radial distance of each gear 16 from the center of the base hub 9, and which is in mesh with said gears 16 and is supported thereon.

From each bearing bracket 13 extends upwardly an auxiliary bracket 19 arranged for a vertical journal. In each auxiliary bracket 19 is journaled an aligning roller 20. These rollers 20 may be made of suitable non-friction material and are located opposite to and in engagement with a side of the ring gear 18. In each set of bearing brackets 13 there are two such auxiliary brackets 19 and aligning rollers 20. The engagement of the opposite sides of the ring gear 18 at spaced points around its circumference by the aligning rollers 20 maintains the ring gear on its rotary track and on the gears 16.

The top of the race frame 17 has an annular dished race 21 thereon. In the present illustration this dished race 21 is formed by a transversely concave lining or insert placed in a hollow recess 22 formed circularly on the top of the race frame 17. At spaced intervals retaining

ribs 23 protrude from the underside of the race lining 21 and engage grooves 24 in the bottom of the recess 22 for anchoring the dished race lining 21 in the recess 22. This dished race lining 21 may be made in several sections or in one piece, as required.

The rotating crushing mechanism 3 for rolling the crusher rollers 4 on said dished race 21 includes a vertical mast structure located centrally with respect to the annular race frame 17 and with respect to the base hub 9. A shaft 25 is journaled at its lower end in suitable thrust bearings 26 in a bearing cup 27 at the bottom of the base 1 and centered inside of the base hub 9. Approximately intermediate between the ends of the vertical shaft 25 is provided another bearing 28 which bearing 28 in turn is supported on suitable braces 29 extended from the top of the base 1. It is to be understood that as many bearings may be provided along the vertical shaft 25 as needed for the steady journalling of said shaft 25. On the top of the shaft 25 is keyed a supporting head 31. In the present illustration the supporting head 31 is held between a collar 32 at its lower end and a securing nut 33 at the top. The supporting head 31 has a plurality of radial arms 34 extended therefrom over and above the dished race 21. In the present illustration the arms 34 are formed by suitable bars or tubes set into sockets 36 in the supporting head 31 and held in place in any suitable manner such as by set screws 37. From each arm 34 are suspended a pair of opposite bearing bracket bars 38. Each bearing bracket bar 38 is pivoted on the arm 34 and is suitably held in position thereon. In the lower ends of the bracket bars 38 is held a roller shaft 39. A crusher roller 4 is journaled on each roller shaft 39 and moves as a wheel on the dished race 21. As the shaft 25 is rotated it rotates the supporting head 31 which in turn carries the arms 34 around and above the dished race 21, and by reason of the pivotal swivelable engagement of the bracket bars 38 on the arms 34 the rollers 4 are pulled along in the nature of heavy wheels and ride in rolling contact on the concave track of the dished race 21 crushing the material in said race 21.

Each roller 4 is made of suitably heavy material and of such weight as to operate as a crusher by its own rolling weight and without any additional pressure thereon. A hub 41 forms the center of each roller 4 and is suitably journaled on the shaft 39. Around the hub 41 is fixed a wheel shoe 42 of suitable thickness and of the type of material which will stand up under wear. The outer periphery of the roller hub 41 is slightly conical, and the inner periphery of the shoe 42 is also conical but in opposite direction to the incline of the periphery of the hub 41. This conical arrangement is comparatively small and just sufficient to provide converging wedge-like annular space 43 into which an annular wedge 44 is driven tightly to hold the shoe 42 on the hub 41. This construction permits the removal of the shoe 42 and its replacement when needed.

It is to be noted that the bracket bars 38 are of such length that when the roller wheels 4 roll upon the dished race 21 the said rollers trail the arms 34. This arrangement allows for a limited pivoting or swivelling of the rollers 4 relatively to the arms 34 and prevents jamming and breakage, and compensates for wear, although it does not impede the crushing action of the rollers 4 which perform the crushing and pulverization by their own weight.

The drive mechanism 6 is such that it rotates simultaneously the race structure 2 in one direction and the rotatable crushing mechanism 3 in the opposite direction in continuous synchronism. In the present illustration the driving mechanism 6 includes a drive shaft 46 which extends through one of the supporting gears 16 and forms its shaft. At the inner end of the drive shaft 46 is a bevel gear 47 in mesh with a horizontal bevel gear 48 keyed on the vertical shaft 25. The drive shaft 46 is driven by any suitable power mechanism such as an electric motor. When the drive shaft 46 is rotated the gear 16 thereon imparts rotation to the ring gear 18 and to the race structure 2. The transmission gears 47 and 48 simultaneously impart rotation to the crushing mechanism in a direction opposite to the direction of rotation of the race structure 2.

The feeding of the ore or the material to be crushed is accomplished in such a manner as to further prevent the piling of material and to provide for uniform distribution of the material around the top of the race structure 2. An annular feed trough 52 is open both at its top and bottom and is provided with a plurality of transverse saddles 53 which latter rest upon the respective radial arms 34 of the crushing mechanism between the supporting head 31 and the rollers 4. The top of the trough 52 has upwardly diverging sides. Skirts 54 extend from the trough 52 downwardly between the saddles 53 for directing the ore. The side walls 56 of the skirts 54 nearer to the rollers 4 are substantially vertical so as to prevent the material from spilling over the rollers 4. The other side walls 57 of the skirts 54 flare inwardly and downwardly toward the center of the machine. A frusto conical shield 58 extends from the inner top corner 59 of the race frame 17 and tapers upwardly past the lower edge of the flaring side walls 57 of the trough skirts 54 so that the material dropping from the trough is guided outwardly and toward the dished race 21. It is to be noted that the top of the race frame 17 in continuation of the shield 58 is inclined toward the dished race 21 to facilitate the flow of material into said dished race 21 and under the rollers 4. The aforescribed feeding structure is rotated and carried with the crushing structure spreading the ore around the race frame 17. The rotation of the race frame 17 exerts centrifugal force for further distribution of the ore evenly around the top of the race frame 17 and toward and into the dished race 21.

For further moistening the material around and in the dished race 21, a pair of outlet nozzles 59 are provided, one on each side of each roller 4. Water or other suitable liquid is conducted to these nozzles 59 by conduits 61 extending along the bracket bars 38, and then joined in one conduit and extending along the arm 34 under the respective saddles 53 and radially at the supporting head 31 to a centrifugal feed chamber 62 formed around the vertical shaft 25 below the collar 32. The upper portion of the shaft 25 is hollow so as to form a passage 63 which is suitably connected to a rotatable joint for receiving water from any suitable source. At the location of the chamber 62 the shaft 25 has a lateral port 64 leading from the shaft passage 63 into said chamber 62. The conduits 61 at their inner ends are connected to ports 66 at the periphery of the feed chamber 62 so that the pressure built up by centrifugal force, as the water is ejected through the ports 66 will force the water through the re-

spective conduits and spray them out at the nozzles 59 along the opposite sides of each roller 4.

The discharge of the ground or crushed material from the race frame 17 is also accomplished in a controlled manner. A substantially cylindrical screen 67 is mounted around the top of the race frame 17 and outside of the rollers 4. In the present illustration, vertical bolts 68 extend upwardly from the race frame 17 near the outer periphery of the said race frame 17. The screen 67 is tightened around the plurality of bolts 68, in the present illustration by providing the free ends of the screen 67 with securing flanges 69 which are tightened together and held by any suitable securing means such as bolts. The screen 67 is of such mesh as to allow the passage only of material of selected density. Therefore, only material crushed to a certain fineness will be permitted to pass through the screen 67. It is to be noted that the rim 71 of the top of the race frame 17 is slightly higher than the top of the dished race 21 so that the material thrown out by the centrifugal force accumulates there gradually and is forced through the screen 67 by said centrifugal force when of sufficient fineness but is allowed to drop back into the race 21 for further grinding if it is not allowed to pass through the screen 67.

The lower corner of the outer periphery of the race frame 17 has an outwardly extended downwardly curved discharge lip 72. The material flowing out through the screen 69 flows down along said lip 72 and is directed downwardly as the race frame 17 is rotated. Around the base 1 and beneath the discharge lip 72 is an annular collecting trough 73 which is held stationary on the base 1 and is so located that the collected material from the discharge lip 72 feeds into this collecting trough 73. One side of this collecting trough 73 is higher and the trough 73 slants downwardly toward the opposite side and has an outlet 74 at its lower side. The crushed ore or material discharged into this collecting trough 73 flows by gravity and washes down and out through the outlet 74 to be there collected and treated in any usual manner.

The pulverizing mill heretofore described is operated very simply because by turning on the power the opposite rotation of the race and the rollers is accomplished in continuous synchronism, the rollers roll in crushing contact on a properly curved and dished race and by reason of the opposite rotation a fine and thorough grinding and pulverizing of the ore is accomplished. The arrangement of the feed trough as it is carried by the roller structure and the centrifugal distribution of the material in opposite directions provide for uniform crushing action along the entire periphery of the race of the mill. The centrifugal discharge of the material as herein controlled assures a uniformity of product. The various groups of elements and combinations of such elements produce a machine which operates with greater efficiency, utilizes less power, does not require any frequent clean-up, it does not require any particular adjustment, it is simple in structure and it is eminently adapted to a variety of materials for which such mills are utilized.

I claim:

1. In a pulverizing machine, a substantially annular race, a supporting device rotating around an axis central with respect to said race, radial arms extended from said supporting de-

vice, crusher rollers, suspending elements supported on said arm and rotatably supporting said rollers in rolling contact with said race, feeding means carried by said arms for directing the material to be crushed onto said race, and a system of liquid conduits on said supporting device and within said arms and said suspending elements conducting liquid to about the center of said rollers.

2. In a pulverizing machine, a substantially annular race, a supporting device rotating around an axis central with respect to said race, radial arms extended from said supporting device, crusher rollers, suspending elements supported on said arms and rotatably supporting said rollers in rolling contact with said race, feeding means carried on said arms for directing the material to be crushed onto said race, and a system of centrifugal liquid feeding conduits extended within said arms and said suspending elements, and outlets on said conduits directed alongside each roller toward said race.

3. In a pulverizing machine, an annular race being transversely dished, a removable lining in said race, means on said lining engaging said race to prevent circumferential shifting of said race, said race being in a substantially horizontal plane, a roller support extended substantially centrally to a level above said race and being rotatable about an axis substantially central to said race, a plurality of crusher rollers riding in said race, means to pivotally support said rollers on said roller support in substantially vertical planes with respect to said race, and means to impart opposite rotation to said support and rollers and to said race.

4. In a pulverizing machine, an annular race, a rotatable support extended approximately centrally of said race and above said race, a supporting hub on said support above the level of said race, a plurality of radial arms extended from said hub to above said race, suspension brackets depending from said arms towards said race and being swingable around the axes of the respective arms, crusher rollers journaled in said suspension brackets and rolling on said race, and means to impart opposite rotation to said support and rollers and to said race.

5. In a pulverizing machine, an annular race, a rotatable support extended approximately centrally of said race and above said race, a supporting hub on said support above the level of said race, a plurality of radial arms extended from said hub to above said race, suspension brackets depending from said arms towards said race and being swingable around the axes of the respective arms, crusher rollers journaled in said suspension brackets and rolling on said race, and means to impart opposite rotation to said support and rollers and to said race, a substantially annular hopper supported on said arms between said hub and said brackets, a substantially annular chute extended from said hopper to below said arms and toward said support, said hopper discharging through said chute, and means on the race extended toward said support and below said chutes to guide the ore from said chutes downwardly towards said race.

6. In a pulverizing machine, an annular race, a rotatable support extended approximately centrally of said race and above said race, a supporting hub on said support above the level of said race, a plurality of radial arms extended from said hub to above said race, suspension brackets depending from said arms towards said

race and being swingable around the axes of the respective arms, crusher rollers journaled in said suspension brackets and rolling on said race, and means to impart opposite rotation to said support and rollers and to said race, a substantially annular hopper supported on said arms between said hub and said brackets, a substantially annular chute extended from said hopper to below said arms and toward said support, said hopper discharging through said chute, and an annular extension on the inside periphery on said race inclined from said guide means outwardly and downwardly to the chute.

7. In a pulverizing machine, an annular race, a rotating support extended substantially centrally and above said race, a supporting hub on said rotating support above the level of said race, radial arms extending from said hub, swiveling brackets depending from said arms, crusher rollers journaled in said brackets and rolling on said race, said central support having a fluid chamber therein communicated with an outside fluid supply, radial outlets on said fluid chamber, a system of radial conduits extended from said outlets generally radially within said arms and then downwardly in said brackets and to said rollers to conduct liquid from said chamber to said rollers, said liquid being expelled through the centrifugal force created by the rotation of said chamber with said support.
